UNITED STATES PATENT OFFICE

CARL V. SHIPLEY, OF CHICAGO, ILLINOIS

AMUSEMENT DEVICE

Application filed November 4, 1929. Serial No. 404,633.

This invention relates to amusement devices.

One object of the invention is to provide in connection with a container, concealed means, normally maintained inactive when the container is resting on a support, for effecting violent vibrations of the container and producing a noise when the container is lifted from the support, thereby causing the person handling the container to be startled or surprised, to the amusement of onlookers.

Another object of the invention is to provide in connection with a container in the form of a box, such as is ordinarily employed as a container for matches, means for effecting vibrations of the box when the same is lifted, wherein the means for causing the vibrations is concealed within the box and is normally held in inoperative condition by means extending through the bottom of the box and held in locking position when the box is resting on a support by engagement with the support and is released by lifting of the box from the support to thereby unlock the vibrating means and permit the same to operate.

A more specific object of the invention is to provide an amusement device in the form of a box having means concealed therein for causing vibrations of the box when the same is lifted, wherein the vibration producing means is of simple construction and inexpensive to manufacture and includes a rotary shaft having a weighted member eccentrically mounted thereon, the shaft and weight member connected thereto being actuated by driving means adapted to be wound, the weighted eccentric member being normally held against rotation by trigger means having a portion projecting through the bottom of the box and engageable with the support on which the box rests to hold the trigger engaged with the weighted member, the trigger being released from holding engagement by lifting the box from the support.

Other objects of the invention will more clearly appear from the description and claims hereinafter following.

50 In the drawings, forming a part of this

specification, Figure 1 is a perspective view of a container in connection with which my improvements are embodied. Figure 2 is a longitudinal, vertical sectional view through the container illustrated in Figure 1 showing the improved vibrating mechanism of my invention. Figure 3 is a vertical sectional view corresponding substantially to the line 3-3 of Figure 2. And Figure 4 is a detailed perspective view, broken away, of certain parts of the winding mechanism of my improved device.

In said drawings, Figure 1 illustrates my improvements as embodied in the conventional form of match box employed for holding safety matches. The box comprises an outer casing 10 and a tray member 11. The casing 10 is open at opposite ends and has spaced top and bottom walls 12 and 13 and spaced side walls 14 and 15. The tray 11, which is telescoped within the casing 10, has the usual bottom wall 16, the usual longitudinal side walls and transverse end walls, and is open at the top. In carrying out my improvements in connection with a container of the type referred to, I preferably mount the vibration producing mechanism within the tray 11 of the box. As clearly shown in Figure 2, the vibrating mechanism proper comprises a weighted member 17 in the form of an eccentric fixed to a horizontally disposed shaft 18 suitably supported in the tray and actuated by any suitable means adapted to be wound. In the form of the invention illustrated in the drawings, the shaft 18 is shown as actuated by a helical spring 19 which surrounds the shaft 18, one end of the spring being fixed to the shaft as indicated at 20 and the other end being secured to a winding element in the form of a gear 21. The corresponding end of the spring 19 may be secured to the member 21 by engaging the extremity of the coil of the spring in an opening provided in the hub of the member 21, although any other suitable manner of securing the same may be employed. The rotary shaft 18 is supported at opposite ends by brackets 22 and 23 which are directly secured to the bottom wall of the tray. The bracket 23 is disposed inwardly of the eccen-

100

tric member 17 and has a journal opening therethrough in which the corresponding end portion of the shaft 18 is rotatably mounted. The bracket 22 is provided with 5 a journal opening in which a reduced portion 24 of the hub of the gear member 21 is rotatable. The gear member 21 is loosely mounted on the corresponding end of the shaft 18 so that the shaft and gear member 10 are relatively rotatable freely with respect to each other. The gear member 21 cooperates with a second gear member 25 which is rotatably supported on a bracket 26 secured to the bottom wall of the tray 11. As shown, 15 the bracket 26 has a pair of horizontal flanges by which the same is secured to the bottom wall of the tray, a horizontal wall spaced above the flanges and vertical walls connecting the horizontal wall and the flanges. The 20 gear 25 is supported on the horizontal top wall of the bracket 26 and is secured to a relatively short shaft 27 which extends through the top wall of the bracket and has a portion 28 thereof projecting below said 25 wall of the bracket. The section 28 as shown is preferably of square cross section so as to cooperate with a winding key 29. Both of the gear members 21 and 25 are provided with teeth 29—29 which are in intermeshing relation, the gear 21 being disposed in vertical 30 position and at right angles to the gear 25. The teeth 29 of the two gears are of like design and are preferably formed by simple stamping operations, each of the teeth 29 being in the form of a projecting finger 35 having a rounded outer end. The gear 25 is rotated in a clockwise direction, as viewed from the top in Figure 4, when the mechanism is being wound by the key 29. Through 40 the inter-engaging teeth of the two gears, the gear 21 is rotated and the spring 19 is wound upon the shaft 18, the shaft being at this time held stationary in a manner hereinafter pointed out. The shaft 27 may be 45 fixed to the gear 25 in any suitable manner and is preferably of such a size as to have a driving fit with the opening in the gear. Below the upper member of the bracket 26, the shaft 27 is provided with a collar 30 bearing on the bottom face of the upper member of the bracket so as to hold the gear 25 in position. The tray 11 of the box and the casing 10 are provided with suitable alined 50 openings 31 and 131 respectively in the bottom thereof through which the key 29 may be inserted for winding the mechanism. 55 In order to prevent backward rotation of the gears 25 and 21, I provide a keeper in the form of a rod or resilient wire member 32. As shown the member 32 has an angularly 60 disposed upper end section which extends through the opening between the legs of the bracket 22 and has the upper extremity thereof projecting between the gears in advance of that point where the teeth thereof

interengage. The bottom horizontal section of the rod or wire 32 is secured to the foot of the bracket 22 in any suitable manner, preferably being welded or soldered to the same. As will be evident, when the mechanism is being wound by the key 29, the upper end section of the member 32 is adapted to yield so as to permit the rotation of the gears. However, when the mechanism has been wound and the spring tends to rotate the 75 shaft 18 and the gear 21 relatively to each other, backward rotation of the gear 21 will be prevented by the keeper 32 becoming jammed between the teeth of the gears 21 and 25. 80

To hold the mechanism in inoperative condition when wound, I provide a trigger 33, the same being pivotally mounted on a bracket 34 secured to the bottom wall of the tray 11. As shown, the trigger has a straight section which extends substantially parallel to the shaft and an angular section 35 which extends downwardly and is curved on the arc of a circle having the pivotal axis of the member 33 as a center. The trigger is so located that when it is disposed in the position shown in Figures 2 and 3, it will engage the side edge of the eccentric 17 and hold the same against rotation in a right hand direction as viewed in Figure 3. The bottom of 90 the tray 11 and also the bottom of the outer casing 10 of the box are provided with alined openings 36—36 through which the curved section 35 of the trigger extends and is adapted to move. As long as the trigger is held in 95 the position shown in Figures 2 and 3, unwinding of the spring 19 is prevented and the member 17 is held inoperative. In order to allow rotation of the member 17, the trigger 33 is permitted to drop so as to clear the 100 path of rotation of the member 17. The dropping of the trigger is effected by lifting the box or container off of the support on which it rests. In Figure 2 the container is 105 illustrated as resting on a support designated by the line 37. Inasmuch as the trigger has the section 35 thereof resting on this support, when the box is on the support the trigger will be maintained in the position shown in Figures 2 and 3. When the box is lifted, 110 the trigger is free to drop through the action of gravity. In order to assist this dropping action of the trigger and assure its movement out of the path of rotation of the member 17, I provide the member 17 with a cam formation on its edge as indicated at 38. The cam face of the member 17 is so designated that it will force the trigger outwardly when the box is held in such a position that the action of the trigger is not influenced by gravity. 115

Endwise movement of the shaft 18, the eccentric member 17 and the gear 21 is prevented by providing the eccentric with a boss 39 on the inner side thereof which bears on the outer face of the vertical section of the brack- 120 125 130

et 23, and a head member 40 at the opposite end of the shaft 18 engaging the outside of the gear 21, it being understood that the reduced section 24 of the gear 21 provides an 5 annular shoulder at the hub of the gear which engages the outer side of the bracket 22. As hereinbefore pointed out, the shaft 18 freely fits within the gear 21 but is fixed to the eccentric member 17. The shaft may be secured to the eccentric member in any suitable manner but preferably has a driving fit in the opening of the same. In assembly of the 10 device, all of the parts are preferably mounted in the tray 11, as hereinbefore described, the parts being secured to the tray before the same is telescoped within the casing 10. As 15 will be evident, the trigger 33, while telescoping the tray within the casing, must be raised to such an extent that the section 35 thereof 20 is entirely withdrawn from the opening 36 of the tray.

In the operation of my improved amusement device, the trigger end 35 is first forced upwardly until it engages the member 17, as 25 shown in Figure 3, to hold the same against rotation while the mechanism is being wound. The key 29 is then applied to the winding member 28 by inserting the same through openings 131 and 31, and the gears rotated 30 through the medium of the stem 28 until the spring 19 has been wound to a sufficient extent. As will be clear at this time, rotation of the eccentric 17 in an unwinding direction will be prevented by the trigger 33, which 35 is disposed in the path of rotation of the eccentric, and has the section 35 thereof supported by the bottom wall of the casing 10. During the winding of the mechanism, the trigger is held in locking position by the operator holding his finger over the opening 36 of the bottom of the casing 10 to prevent the trigger from dropping down. After the mechanism has been wound, the container is 40 placed on a support, such as the support indicated by 37, and inasmuch as the section 35 of the trigger at this time rests upon the support, the weight of the container will maintain the trigger in the position shown in Figures 2 and 3. When the container is 45 lifted, the trigger 33 will be free to drop down, thus clearing the path of rotation of the eccentric 17 and permitting very rapid rotation of the same through the medium of the spring 19. Due to the eccentric 17 being 50 weighted and being rotated rapidly on its eccentric axis, violent vibrations will be set up with an accompanying noise, due to the rapid movement, thus causing surprise to the party lifting the container, to the amusement 55 of others.

In order to prevent accidental operation of the eccentric member 17 while the container is being handled or the mechanism is being wound, I preferably provide a pivoted 60 stop member 40 in the form of a plate mount-

ed on a pivot pin 41 extending into the bottom wall of the casing 10. As will be clear, upon reference to Figure 2, when the pivoted plate 40 is swung so as to close the opening 36 in the bottom wall of the casing, the plate will act as a stop, preventing downward movement of the trigger 33. When it is desired to have the mechanism operate, the pivoted plate 40 is swung to one side so as to clear the opening 36 in the bottom wall of the casing to allow the section 35 of the trigger to drop therethrough.

Although I have shown my improvements in the drawings, as embodied in a match box structure, it will be appreciated that my invention is not limited thereto, my improvements being adapted for use in connection with any type of container or package which when resting on a support will maintain a controlling member in such a position as to hold the motion creating vibrating means inoperative and will permit operation of the vibrating means by movement of the controlling means when the container or package is lifted.

It is further pointed out that my improvements are not necessarily limited to operation of the device by lifting the same from a support, it being possible to operate the same by holding the package in the hand and placing a finger over the opening in the container through which the actuating member of the controlling means operates so as to maintain the controlling means in position to hold the vibrating mechanism inoperative, and removing the finger from the opening when the package is handed to another person to permit the controlling means to be forced outwardly either by the camming action of the eccentric or to drop by gravity, thereby allowing the vibrating means to operate, causing vibrations of the package and noise, as hereinbefore pointed out.

I have herein shown and described what I now consider the preferred manner of carrying out my invention, but the same is merely illustrative and I contemplate all changes and modifications that come within the scope of the claims appended hereto.

I claim:

1. In an amusement device, the combination with a container adapted to rest on a supporting means; of means within the container for effecting vibration of the container; and means for controlling the operation of said first named means, said controlling means normally projecting through a wall of the container and maintaining the first named means in inoperative condition by engagement with said supporting means, said controlling means being moved relatively to the container by lifting the container from said supporting means, thereby throwing the vibrating means into operation.

2. In an amusement device, the combination with a container; of means within the container for effecting vibration of the same; and a finger projecting through a wall of the container for controlling the operation of said first named means, said finger being urged outwardly, said finger when pushed inwardly and maintained in said position holding said first named means inoperative and when released, being projected outwardly, thereby releasing the vibrating means to allow operation thereof.

3. In an amusement device, the combination with a container; of means within the container for effecting vibration of the same; and means for controlling the operation of said first named means, said controlling means in one position holding said first named means inoperative and in another position releasing the same to allow operation thereof, said controlling means, when the container is resting on a support, engaging said support and being held in said first named position by the weight of the container, said controlling means moving to releasing position by lifting of the container from the support.

4. In an amusement device, the combination with a container; of means within the container for effecting vibration of the same; and means for controlling the operation of the first named means including a member projecting through the bottom of the container and adapted to engage an obstruction, said controlling means in one position maintaining said first named means inoperative and in another position releasing the same to permit operation thereof, said controlling means being held in said first named position by said member by engagement of the member with the obstruction, and being movable to said second named position when the obstruction is displaced.

5. In an amusement device, the combination with a container adapted to rest on a support; of means within the container for effecting vibration of the same; and means for controlling the operation of the first named means including a member projecting through the bottom of the container and adapted to engage said support, said controlling means in one position maintaining said first named means inoperative and in another position releasing the same to permit operation thereof, said controlling means being held in said first named position by said member when the container is resting on the support, by engagement of said member with the support and being moved to said second named position when the container is raised from the support to permit operation of the vibrating means.

6. In an amusement device, the combination with a container adapted to rest on a support; of means concealed within the con-

tainer for effecting vibrations of the same, including a weighted member rotatable about an eccentric axis; and a trigger member co-operating with said weighted member, said trigger member in one position thereof locking said weighted member against rotation and in another position thereof releasing the same, said trigger member having a portion thereof extending through the bottom of the container and adapted to contact with said support to hold the trigger in engagement with said weighted member when the container is resting on said support, said trigger member being moved to said second named position to release the weighted member by lifting the container from the support.

7. In an amusement device, the combination with a container adapted to rest on a support; of a rotary shaft mounted within the container; a weighted member eccentrically connected to the shaft; means adapted to be wound for effecting operation of said shaft and weighted member; and a trigger for controlling the operation of said weighted member, said trigger having a portion thereof extending through the bottom of the container and engaging said support to hold the trigger in position to prevent operation of said shaft and weighted member when the container is resting on the support.

8. In an amusement device, the combination with a container; of a weighted member within said container rotatable about an eccentric axis to effect vibration of the container; means adapted to be wound for effecting rotation of said member; and trigger means for controlling the operation of said member, said trigger means having a portion by which the same is actuated, said portion projecting through a wall of the container.

9. In an amusement device, the combination with a container adapted to rest on a support; of a member within the container mounted for rotation about an eccentric axis; a movable locking trigger adapted to be interposed in the path of rotation of said member to prevent operation thereof, said trigger having a portion by which the same may be actuated extending through the bottom of the container, said trigger being normally forced outwardly and being normally disposed in the path of rotation of said eccentrically mounted member and adapted to be engaged by the support to be held in the path of movement of said eccentrically mounted member.

10. In an amusement device, the combination with a container; of an eccentric mounted in said container; means adapted to be wound for actuating said eccentric and rotating the same at high speed; and movable trigger means for controlling the operation of said eccentric member having an arm extending through a wall of the container and

adapted to project therefrom, said trigger being movable to a position inwardly of the container to hold the eccentric against rotation.

5 11. In an amusement device, the combination with a container; of an eccentric rotatably mounted in said container; means for actuating said eccentric and rotating the same at high speed; and movable means for controlling the operation of said eccentric member; said movable means having an arm extending through an opening in the wall of the container and projecting outwardly of the container, said arm being displaceable 10 inwardly of the box to position said controlling means to hold the eccentric against rotation, and said arm being forced outwardly of the container by the action of said eccentric to release the eccentric and permit 15 rotation of the same.

20 12. In an amusement device, the combination with a container; of a shaft rotatably mounted within the container and having a weighted eccentric fixed to one end thereof; means adapted to be wound for rotating said shaft; and means for winding said last named means including a pair of cooperating gear members having interengaging teeth; and means engaging between the gear 25 30 teeth adapted to jam when said gears are rotated in one direction and adapted to yield when the gears are rotated in the reverse direction during the winding movement thereof.

35 13. In an amusement device, the combination with a container; of a shaft rotatably mounted in the container and having a weighted eccentric fixed to one end thereof; means for rotating said shaft including a 40 spiral spring having one end fixed to said shaft; and means for winding said spring including a gear member loosely mounted on the rotatable shaft and having the other end of the spring fixed thereto, said gear 45 being held against rotation in an unwinding direction.

14. In an amusement device, the combination with a container comprising a casing open at opposite ends and a telescoping tray 50 slidably disposed within the casing; of an eccentric rotatably mounted within the tray; means adapted to be wound for actuating said eccentric also mounted in the tray; and movable trigger means for controlling the 55 operation of said eccentric member, said trigger means being mounted in the tray and having an arm adapted to project through an opening provided in the bottom of the tray.

60 15. In an amusement device, the combination with a container adapted to be placed on a supporting surface; of means within the container for effecting vibration of the container; and means controlling the operation of said first named means, said con-

trolling means normally maintaining the first named means in inoperative condition and being held in said condition by contact with the supporting surface when the container is resting thereon, said controlling means 70 being released by removing the container from the supporting surface to thereby set the vibrating means in operation.

In witness that I claim the foregoing I have hereunto subscribed my name this 23rd 75 day of October, 1929.
